UNITED STATES PATENT OFFICE.

BERTHA BLOOM, OF WOODCLIFF, NEW JERSEY, ASSIGNOR TO MAX SCHULTZ, OF WOODCLIFF, NEW JERSEY.

JEWELRY-CLASP.

1,377,552.

Specification of Letters Patent. Patented May 10, 1921.

Application filed February 5, 1921. Serial No. 442,674.

To all whom it may concern:

Be it known that I, BERTHA BLOOM, a citizen of the United States, residing at Woodcliff, in the county of Hudson and State of New Jersey, have invented a certain new and useful Improvement in Jewelry-Clasps, of which the following is a specification.

The invention relates to fastening means for separably joining the ends of flexible bracelets, collars, and the like, and the object of the invention is to provide a clasp which will engage automatically, hold reliably, and may be easily and economically manufactured.

15 The invention consists in certain details of construction and arrangement by which the above objects are attained, to be herein-after described and claimed.

20 The accompanying drawings form a part of this specification and show the invention as it has been carried out in practice.

Figure 1 is a face view of the clasp in the fully locked condition, with its two members shown attached to the ends of a bracelet.

25 Fig. 2 is a section taken longitudinally of the clasp, on the line 2—2 in Fig. 1, with certain portions omitted.

Fig. 3 is a transverse section taken on the line 3—3 in Fig. 1.

30 Fig. 4 is a face view of the inner member carrying the locking staple.

Fig. 5 is a similar view of the outer member in which is the slot for the reception of the staple.

35 Fig. 6 is a face view of the clasp alone, corresponding to Fig. 1, showing the members in the partially engaged position or conditioned for disengagement.

Referring to the drawings, 1 is the inner 40 member and 2 the outer member, both shown as flat plates of rectangular outline with rounded corners and approximately the same length and width, but the forms and relative sizes may be varied.

45 On the lower member is an outwardly projecting loop or staple 3 shown as formed integrally with the plate 1, and in the plate 2 is a slot 4 adapted to inclose the staple 3 with the latter projecting therethrough sufficiently to receive a spring-ring 5 or other removable locking means serving to prevent the withdrawal of the staple from the slot. The spring-ring 5 is shown as attached to the outer member 2 by a chain 6.

The strands forming the body of the 55 bracelet 7 are attached at one end to rings 8 in the side margin of the member 1, and at the other to rings 9 mounted in the side margin of the member 2, thus completing the band.

60 The slot 4 is of such dimensions as to permit the staple 3 to pass through in the engaging and disengaging operations, and has two lateral portions or recesses 10, one at each end of the longitudinal slot 4, extending at right angles to the latter and both in the same direction, the metal between forming a tongue 11 lying in the plane of the member 2.

65 When the staple is inserted in the slot 4 the tension of the bracelet automatically draws the legs of the staple into the lateral portions or recesses 10 with the tongue 11 engaged in the staple. Thus conditioned the staple is held and the two members can- 70 not be separated. The spring-ring 5 is then engaged in the bight of the staple as a safeguard against disengagement.

75 So long as the bracelet is under tension the tongue 11 maintains its engagement and the bracelet must be shortened slightly by sliding the members 1 and 2 upon each other to permit the staple to register with the longitudinal slot 4 in the operation of opening the clasp.

80 Modifications may be made in the forms and proportions of the parts in adapting the invention to various articles of jewelry or to other articles of the belt or band type. The spring-ring 5 may be omitted or other fas- 85 tening means as a pin or padlock may be substituted.

I claim:—

90 In a device of the character set forth, an inner member having an outwardly projecting staple, and an outer member having a slot and recesses adapted to receive said staple, a tongue on said outer member between such recesses, arranged to enter said staple and prevent the separation of the 95 members, and a removable locking means received in said staple exterior to said outer member.

100 In testimony that I claim the invention above set forth I affix my signature.

BERTHA BLOOM.
